(57) **CLAIM**

The ornamental design for an electrical box with adapters, as shown and described.

DESCRIPTION

FIG. 1 is a perspective view of our new design for an electrical box with adaptors with a ceiling adaptor;

FIG. 2 is a top view thereof;

FIG. 3 is a bottom view thereof;

FIG. 4 is a side view thereof;

FIG. 5 is an opposite side view thereof;

FIG. 6 is a different side view thereof;

FIG. 7 is an opposite side view thereof;

FIG. 8 is a perspective view of a second embodiment of the electrical box with adaptors showing our new design with a two gang adaptor;

FIG. 9 is a top view thereof;

FIG. 10 is a bottom view thereof;

FIG. 11 is a side view thereof;

FIG. 12 is an opposite side view thereof;

FIG. 13 is a different side view thereof;

FIG. 14 is an opposite side view thereof;

FIG. 15 is a perspective view of a third embodiment of the electrical box with adaptors showing our new design with a single gang adaptor;

FIG. 16 is a top view thereof;

FIG. 17 is a bottom view thereof;

FIG. 18 is a side view thereof;

FIG. 19 is an opposite side view thereof;

FIG. 20 is a different side view thereof;

FIG. 21 is an opposite side view thereof;

FIG. 22 is a perspective view of a fourth embodiment of the electrical box with adaptors showing our new design with a four square adaptor;

FIG. 23 is a top view thereof;

FIG. 24 is a bottom view thereof;

FIG. 25 is a side view thereof;

FIG. 26 is an opposite side view thereof;

FIG. 27 is a different side view thereof; and,

FIG. 28 is an opposite side view thereof.
